UNITED STATES PATENT OFFICE.

WACLAW WOLSKI, OF LEMBERG, AUSTRIA-HUNGARY.

HYDRAULIC DRILL.

No. 842,049.

Specification of Letters Patent.

Patented Jan. 22, 1907.

Application filed June 22, 1906. Serial No. 322,806.

To all whom it may concern:

Be it known that I, WACLAW WOLSKI, a subject of the Emperor of Austria-Hungary, residing at Lemberg, Galicia, in the Empire of Austria-Hungary, have invented a new and useful Hydraulic Drill, of which the following is a specification.

There are known hydraulic drills for deep-well boring purposes in which the live force of the rinsing-water automatically and suddenly closes a spring-pressed valve and acts upon a piston for striking the drill on the bottom of the bore the moment the speed of the water has attained a certain limit. Thus the motion of the valve in these devices is controlled by the speed of the rinsing-water passing through the opened valve.

My invention relates to an improvement in such hydraulic drills whereby in opposition to the known devices the motion of the drill is utilized for opening and closing the valve.

The object of my improvement is to provide two helical springs between which the valve is held, so that it is permitted to swing upward and downward.

I will now proceed to describe my invention with reference to the accompanying drawings, in which—

Figure 1 is a vertical longitudinal section through a hydraulic drill, the lower part of the drill proper being shown in elevation; and Fig. 2 is a plan of the valve.

The drill proper, M, is guided in a tube A and in its two slots *a a* and is rigidly connected with a hollow piston K by means of a tube R. The piston K is guided in a stuffing-box B of any known construction, and its upper face serves as a seat for a valve P, as is well known. The valve P is shown as provided with four arms *p p*, the ends of which are guided in a cylindrical vessel C. The stuffing-box B is rigidly connected with the tube A by means of an intermediate tube D with the aid of screw-threads, as shown. The neck V of the vessel C is connected with the known hollow pump-rods and suspended therefrom. The vessel C and the parts A and D form a tubular casing for the interior operative parts of the drill. These hollow pump-rods should be provided with an air-vessel, as usual. The piston K is provided at its lower end with a flange *k*, and a helical spring F, tapering upward, is inserted between this flange *k* and the shoulder of the

tube A, as usual, for pressing the piston K upward. The valve P is inserted between two helical springs *f'* and *f''*, of which the upper spring *f'* bears against the top of the vessel C and the lower spring *f''* bears on the stuffing-box B. Normally the valve P is held by the two springs *f'* and *f''* at a certain height above the upper face of the piston K and can swing upward and downward.

The hydraulic drill operates as follows: When the water from the respective pump is turned on, it will flow downward through the hollow pump-rods, enter the vessel C, pass beneath the valve P, and flow through the hollow piston K, the tube R, and the bore *m* of the drill proper, M. After striking the bottom of the bore this water will flow upward through the annular space between the walls of the bore and the outside of the tubes A and D and the vessel C, while rinsing the bore, as usual. When the increasing speed of the water attains a certain limit, the live force of the water will close the valve P, and the so-produced hydraulic-ram pressure will throw the valve P and the piston K, with the tube R and the drill M, downward, so that the edge of the drill M will strike the bottom of the bore. Of course during this time the helical spring F will be compressed, as usual, and also the helical spring *f''*. The moment the live force of the water is exhausted it will be overbalanced by the tension of the compressed helical springs F and *f''*, so that the helical spring *f''* will detach the valve P from the upper face of the piston K and permit the water to reenter the cavity of the piston K. At the same time the helical spring F will force the piston K, with the tube R and the drill M, upward, while raising their weight until the upper face of the piston K touches the valve P, or nearly so, whereby of course the passage of the water through the piston K is stopped. The hydraulic-ram pressure so produced—that is, the live force of the water—will then throw the valve P, with the piston K, the tube R, and the drill M, downward to produce the blow of the drill on the bottom of the bore. Henceforward all the occurrences will repeat.

It is evident that the length of each period or the number of blows per minute will have to depend upon the ratio between the tension of the helical spring F and the own weight of the piston K, the tube R, and the drill M and that the strength of the blow of the drill will

have to depend upon the pressure in the pump which influences the live force of the water.

Of course the hydraulic drill may serve all 5 boring purposes of every description. It is equally obvious that the apparatus may be used for other purposes—such as kerving, stemming of joints, riveting, &c.—after the drill M has been replaced by the respective 10 tool.

What I claim as my invention, and desire to secure by Letters Patent, is—

1. In a hydraulic drill, the combination 15 with a tubular casing adapted to be connected with a hollow pump-rod and to be suspended therefrom, of a stuffing-box in said tubular casing forming two chambers therein, one above and one below said stuffing-box, a piston guided in said stuffing-box and formed 20 as a tube, a drill guided in the lower part of said tubular casing and having a bore for the rinsing-water, a tube connecting said drill with said piston, a helical spring in the lower chamber of said tubular casing and bearing 25 with its upper end on said piston and with its lower end on a shoulder of said tubular casing, a plate with a plurality of arms guided in the upper chamber of said tubular casing and adapted to periodically close as a valve the 30 cavity of said piston, two helical springs in the upper chamber of said tubular casing on both sides of said plate and adapted to normally hold the latter at a height above said piston.

35 2. In a hydraulic drill, the combination

with a cylindrical vessel having a neck which is adapted to be connected with a hollow pump-rod and to be suspended therefrom, of a stuffing-box screwed into the lower end of said cylindrical vessel, a piston vertically 40 guided in said stuffing-box and formed as a tube with a flange at the lower end, a plate with a plurality of arms guided in said cylindrical vessel and adapted to periodically close as a valve the cavity of said piston, a first helical spring inserted between said plate and the shoulder of said cylindrical vessel, a second helical spring inserted between said plate and said stuffing-box, a vertical tube screwed on said stuffing-box, a vertical 45 guiding-tube screwed into the lower end of said vertical tube, a helical spring tapering upward and inserted between the flange of said piston and the upper face of said vertical guiding-tube, a drill guided in said vertical guiding-tube and having a bore for the rinsing-water, and a tube screwed at its upper end into said piston and at its lower end into said drill, said first helical spring and said second helical spring being adapted to normally hold said plate at a height above said piston.

In testimony whereof I have signed my name to this specification in the presence of two subscribing witnesses.

WACLAW WOLSKI.
